PURSE MOUNTING FOR HANDBAGS

Filed Sept. 10, 1938

UNITED STATES PATENT OFFICE

2,182,563

PURSE MOUNTING FOR HANDBAGS

George Landberg, New York, N. Y.

Application September 10, 1938, Serial No. 229,249

4 Claims. (CL 150—29)

This invention relates to purse mountings for handbags.

One object of the invention is to provide an improved mounting as described which shall not necessitate any change in the purse construction nor require any special or separate parts for mounting the purse in the handbag.

Another object of the invention is to provide an improved means for utilizing the slide fastener 10 stringers for mounting the purse in the handbag.

Another object of the invention is the provision of improved means for mounting a purse on a handbag by clamping directly in the frame channels of the handbag, as by means of prongs, or the like.

A further object of the invention is to furnish a device as described having few and simple parts, and which is durable, reliable and efficient in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a view in front elevation showing a device embodying the invention, in closed position thereof.

Fig. 2 is a top plan view thereof in open position.

Fig. 3 is an enlarged sectional view taken on the line 3—3 of Fig. 2.

Fig. 4 is an enlarged view in side elevation of the purse and parts of the mounting, with certain parts broken away and in section.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a device embodying the invention and exemplifying one form of my improved purse mounting for

handbags. The device 10 may include any conventional handbag having a bag body 11, preferably of the type which is provided with a frame. The latter may include inverted U-shaped frame members 12 hingedly interconnected as at 14. 5 Desirably the frame members are of channel form, and I have found that outwardly opening channels are particularly desirable. For example, the channel may include an inner flange 15, an outer flange 16, a back 17, and an external finishing flange 18, if preferred. In this channel the bag body 11 is marginally secured as at 19 by clamping the outer flange 16 inward. This construction may be uniform at the top and ends of the bag body, with the end gussets extending from 15 the frame in the usual manner as indicated at 20.

Within the bag body 11 is supported or suspended a purse 21, preferably of the type having any well known fastener such as a slide fastener closure 22 along the top thereof and terminating at the ends of the purse. However, the stringers 23 which form a part of the slide fastener, provide end portions 24 which project beyond the adjacent end portions of the purse. 25 These end portions 24 may be suitably interconnected as by a usual stop clip 25 for the slider 26, and by tacking 27, if desired. To support the purse 21, the stringer end portions 24 are suitably attached to the end walls of the bag body 30 11, preferably by being clamped in the frame channels, adjacent to the hinges 14.

For securing of the stringer end portions 24 without interfering with the engagement of the bag body in the frame channels as at 19, the outer flanges 16 are preferably slotted as at 28 35 to provide tongues or prongs 29 which can be bent and tightly clamped on the end portions 24. These prongs may be spaced above the hinge axis with the portions 24 being separable in course of 40 opening and closing the frame. This arrangement permits the bag body 11 to be attached to the frame, and permits the purse to be thereafter secured by the prongs 29 or vice versa. Each operation can be carried out without interfering with the other. When the described attachment at the prongs 29 has been effected, the mounting of the purse is completed, and the latter may otherwise be wholly free of any other supporting action or engagement with the frame 45 or with the bag body.

Since each arm 30 secures one stringer end portion, the purse 21 is centrally supported and the thickness of the stringers is distributed for neatness and ease of assembling. A double 50 55

anchorage is thus effected for each end of the purse.

By using outward opening channels, the prongs 29 are concealed as shown in Fig. 2, and the frame 5 appears smooth and unbroken. The most uniform results may be attained by forming cut outs 31 in the outer flanges 16 for leading in the stringers under the prongs 29. This has the further advantage of permitting slightly greater 10 elevation in the purse so that it is nearer to the mouth of the bag body 11. And of course the prongs 29 are spaced above the hinge axis for a similar purpose. If desired, the top of the purse may be upwardly convexed to form a projection 15 32 to bring the purse still nearer to the mouth of the bag body. The side walls of the purse may be stiff or may have stiffening plies therein to maintain the shape of the bag. In any case, the stringers may serve to hold the slide fastener 22 20 taut or to prevent collapse thereof when the slider is being operated, or at least to reliably support the purse, since the stringers are relatively heavy and tough and possess considerable strength.

It will be noted that with the present invention 25 a purse may be mounted on the handbag frame by the securing or clipping of projecting end portions of the purse to the frame as within the channels thereof, to avoid the need for intermediate parts. The invention permits this general result to be accomplished without any positive change in the purse structure, and without requiring additional parts or steps in the assembling.

I claim:

- 35 1. A purse mounting for handbags, including a frame for a bag body, having inverted U-shaped channel frame members providing pivotally interconnected arms, a purse within the bag body, having a slide fastener closure, the latter providing 40 stringers projecting beyond the end portions of the purse, said stringer end portions being clipped to the frame members within the channels thereof adjacent to the pivot points so that each of said arms secures one of said end portions 45 to support the purse in central relation to the frame, and the end portions of the purse being otherwise free of the frame.
2. A purse mounting for handbags, including a frame for controlling the opening and closing of 50 a bag body, said frame comprising inverted U-shaped frame members having hingedly inter-

connected arms at the ends of the bag body, said frame members having outwardly opening channels in which the bag body is clamped, the outer flanges of the channels being undercut adjacent to the hinges, the said outer flanges being slotted to provide prongs immediately adjacent to the undercuts, a purse adapted to lie in the bag body and having an opening and a slide fastener therefor terminating at the ends of said opening, the latter having stringers having end portions extending beyond the ends of the bag body, each of said arms engaging one of said end portions with the latter passing through said undercuts and being clamped by said prongs.

3. A purse mounting for a handbag, including a frame for controlling the opening and closing of a bag body, said frame comprising U-shaped channel frame members having hingedly interconnected arms at the ends of the bag body, a purse within the bag body, having a slide fastener closure, said purse having tapes extending along the slide fastener closure and projecting beyond the end portions of the purse, the projecting end portions of the tapes being clipped to the frame members within the channels thereof adjacent to the hinge connections so that each of said arms secures one tape end portion to support the purse in central relation to the frame, and the end portions of the purse being otherwise free of the frame.

4. A purse mounting for a handbag, including a frame for controlling the opening and closing of a bag body, said frame comprising U-shaped channel frame members having hingedly interconnected arms at the ends of the bag body, a purse within the bag body, having a slide fastener closure, said purse having tapes extending along the slide fastener closure and projecting beyond the end portions of the purse, the projecting end portions of the tapes being clipped to the frame members within the channels thereof adjacent to the hinge connections so that each of said arms secures one tape end portion to support the purse in central relation to the frame, the outer flanges of said arms having bent prongs for clipping engagement with the projecting end portions of the tapes, said prongs projecting toward the respective adjacent ends of the bag body, and the end portions of the purse being otherwise free of the frame.

GEORGE LANDBERG.
